ATTORNEYS.

UNITED STATES PATENT OFFICE.

CHARLES N. FORREST, OF RAHWAY, NEW JERSEY, ASSIGNOR TO THE BARBER ASPHALT COMPANY, OF PHILADELPHIA, PENNSYLVANIA, A CORPORATION OF WEST VIRGINIA.

BUILDING CONSTRUCTION.

Application filed September 23, 1925. Serial No. 58,019.

My invention relates to building construction and the like, and is especially adapted and advantageous for structures such as exterior walls of buildings, and particularly 5 walls of hollow tile, brick, concrete, or concrete blocks, etc., into which nails cannot be driven. The invention is particularly concerned with the application of flexible "stucco base," as it is termed, to such walls. 10 Flexible bituminous stucco base such as described in U. S. patent to Applegate No. 1,138,069 is a product resembling mineral surfaced bituminous roofing, and is made by saturating and coating bibulous paper or rag 15 felt with bitumen and embedding coarse mineral granules in the bitumen while it is still soft. Various advantages that can be realized from my invention will appear from my description hereinafter of a selected and 20 preferred embodiment.

In the drawings, Fig. I is a fragmentary perspective view of a wall embodying my invention, partly in section and with the exterior layers partly broken away to illustrate 25 various stages in the construction of such a wall.

Fig. II illustrates a somewhat different form of construction.

In building a wall of impenetrative character such as described above, I provide for 30 the attachment of stucco base by means of penetrable insets suitably distributed in the wall. Such insets may consist of wooden strips 5 laid horizontally between courses 35 or units of the hard material forming the

wall, at intervals such as six inches or twelve inches (e. g. between successive courses of hollow tile or concrete blocks), and permanently cemented into the structure. Or, if preferred, the insets may consist of courses 40 or units of penetrable character like blocks of cinder concrete 6 laid in alternate courses with impenetrable material at about twelve inch horizontal intervals, for example. As is obvious, the cinder concrete may be laid 45 in a plastic condition so as to bind together the hard units.

The wall having been built with such penetrable insets, the gritted stucco base 7 is laid against the wall and fastened with nails 8 50 driven through it into the insets. After this, plaster or stucco 9 may be applied to the base with a trowel, a float, or in any other suitable manner.

Having thus described my invention, I 55 claim:—

A wall structure comprising a wall composed of courses of impenetrable hard units with intervening courses of penetrable cinder concrete units laid in plastic condition 60 and serving to bind together adjacent hard units, flexible stucco base secured to the wall by nails passing into the cinder concrete units, and a layer of stucco carried by the base. 65

In testimony whereof, I have hereunto signed my name at Maurer, N. J., this 17th day of Sept., 1925.

CHARLES N. FORREST.
